Primary Examiner — Omeed Agilee(74) *Attorney, Agent, or Firm* — Gearhart Law, LLC;
 David Postolski(57) **CLAIM**

The ornamental design for a hexagonal package, as shown and described.

DESCRIPTION

FIG. 1 is a perspective view of a hexagonal package showing my new design.

FIG. 2 is a front elevational view thereof, the rear elevational view being a mirror of FIG. 2.

FIG. 3 is a left side elevational view thereof, the right side elevational view being a mirror of FIG. 3.

FIG. 4 is a top plan view thereof; and,

FIG. 5 is a bottom plan view thereof.

1 Claim, 4 Drawing Sheets(56)
